UNITED STATES PATENT OFFICE.

WILLIAM FREEDMAN, OF BROOKLYN, NEW YORK.

DETACHABLE AND REVERSIBLE COLLAR FOR BLOUSES.

1,113,977.

Specification of Letters Patent. Patented Oct. 20, 1914.

Application filed March 28, 1914. Serial No. 827,786.

To all whom it may concern:

Be it known that I, WILLIAM FREEDMAN, a citizen of the United States, residing in the borough of Brooklyn, in the county of 5 Kings and State of New York, have invented a new and useful Detachable and Reversible Collar for Blouses, of which the following is a specification.

My invention relates to a detachable and 10 reversible collar intended principally but not exclusively for what is known as a middy blouse, and the objects of my invention are: to enable the wearer to use one garment in the place of three; to prolong 15 the use and enjoyment of the garment because it will be washed and cleaned more easily and readily, and with no damaging effect upon the collar which is the most prominent part; to pecuniarily benefit the manufacturer. These objects are attained 20 by the means and mechanism illustrated in the accompanying drawing, in which—

Figure 1 is a view of the collar detached 25 from the blouse; Fig. 2 is a view of the collar attached to the blouse; Fig. 3 is a vertical section view of a modified form of the flap of the collar.

Similar numerals refer to similar parts 30 throughout the several views.

The collar 1 consists of two pieces of 35 cloth one shown at 2 colored blue and the other shown at 3 being red. They are sewed together at the edges and are cut in the form and pattern shown in Fig. 1. It has three straight sides the fourth being 40 horseshoe shaped and cut so as to fit the neck of the wearer. The collar 1 has three appendages or projecting portions one on the left side, one in the center 11 and another on the right side. The appendages on 45 the left and right sides are triangular shaped so that when the collar 1 is attached to the blouse 9 these two appendages fit in under the respective lapels 14 and 19 of the blouse. In the appendage on the left side 50 there is a button hole 6 which is cut vertically as indicated in Fig. 1. It is located so that when the collar 1 is placed upon the blouse 9 as in (Fig. 2) it will coincide with the button 7 sewed on to the blouse 9 under 55 the left lapel 19 and likewise with the button hole 18 in the left lapel. Similarly button hole 5 is vertically cut and is located so that it will coincide in a similar manner on the right side. The button hole 4 in the center appendage or flap 11 is cut horizontally or

vertically and is so located that when the collar 1 is properly placed upon the blouse it will coincide with the button 12 sewed on to the back of the blouse 9 from the inside. 60

The collar 1 is attached to the blouse 9 by means of buttons 7 which are sewed on to the upper portion of the blouse each under one of the button holes 18 and 8 located in the lapels 14 and 19. The flap 11 65 is attached to the blouse by means of button hole 4 and button 12 which is buttoned through it. The button 12 on which the flap is attached is sewed on to the back of the blouse 9 on the inside. The lapels 19 70 and 14 are triangular shaped like those in ordinary coats and in the upper part of each is a button hole 18 and 8 respectively which is cut either vertically or horizontally. Hence in order to attach the collar 1 to the blouse the buttons 7 are first buttoned 75 through the button holes 6 and 5 and then through button holes 18 and 8 and button 12 is buttoned through button hole 4. When this is done the collar is attached and will 80 then look as indicated in Fig. 2.

The flap, Fig. 3, also 11 in Figs. 1 and 2, is semi-circular. In Fig. 1, it is a part of the collar and is made of the same material. It consists of two parts red and blue just like 85 the rest of the collar. In the center it has a button hole 4 cut horizontally or vertically, preferably the former. The flap may as in Fig. 3, consist of three pieces of white material 15, 16 and 17 and is sewed together 90 at the edges. In the top, 15, and bottom, 17, parts of this flap are button holes, 4. The middle part, 16, is inserted to prevent the button, 12, which is sewed on to the inside of the blouse, 9, and which is used to attach 95 the flap, 11, to the blouse, 9, from pressing against the wearer's neck when the garment is worn, and also from being seen, when not worn. This is so because when attached to the blouse 9 the button 12 slips in between 100 the two parts 16 and 17 and when reversed between the parts 16 and 18, thereby causing the button 12 always to come under the middle part 16. By buttoning the flap, 11, on the button 12, the collar, 1, sets firmly on 105 the blouse, 9, and gives it the appearance of being actually sewed on.

I prefer to use ordinary buttons 7 as a means of attaching the collar 1 to the blouse 9 but any other means of fastening such as 110 clasps or patent buttons may be used.

In carrying out this invention, the use of

a flap like the one shown in Fig. 3, is much more preferable to the one 11 indicated in Figs. 1 and 2, and, as above indicated the former will prove of much more convenience to the wearer than the latter. However either may be used in manufacturing the collar.

The collar on the ordinary middy blouse is sewed to the garment. The collar is usually made of a different material often cloth, which is colored either red or blue, these being the two most favorite colors demanded by the trade, while the body of the blouse is made of white material.

15 By the use of my invention, the wearer may whenever it is desirable, detach the collar from the blouse and reverse it and again attach it and vice versa, thereby enabling her to use one garment in the place of two viz: one with a blue collar and another with a red one. Besides the blouse itself with the collar detached can be worn and is an especially convenient and comfortable garment in summer.

20 The ordinary middy blouse, because it consists mostly of white material soils very easily and quickly. It, therefore, must be washed very often. However, the collar being sewed on to the blouse must also be washed every time the blouse is washed, and since the collar is made of colored material, great care must be exercised in preventing it from fading and the color from running, besides making it very difficult to wash because it can not stand boiling. By frequent washing the best of colored material is spoiled, and therefore the blouse can not be worn, because the collar loses its original

color. By having a detachable collar all this inconvenience is dispensed with. The collar is removed and the blouse may then be boiled and washed as all other white goods are. The collar may be washed separately in a suitable manner, and because it soils less quickly than the rest of the blouse, since it is colored, is washed less often thereby prolonging its usefulness.

Ordinarily the blouse must be washed together with the collar, and therefore the manufacturer must use an exceptionally fine quality of cloth in manufacturing it, in order to withstand the frequent and rough washing. By using this invention, the manufacturer can use a cheaper quality of cloth and get better service out of it.

25 I claim as new and desire Letters Patent for:

A detachable and reversible collar for a garment having lapels in front and fastening means beneath the lapels, the collar comprising an extended flat body to hang down the wearer's back, and being provided with an incut side to fit around the back of the wearer's neck and with projecting portions at the ends of said side and another projection at the middle of said side, the last-named projection being adapted to be secured to the back of the garment, and the other projections being adapted to pass forward over the wearer's shoulders and be secured beneath the lapels by said fastening devices.

30 WILLIAM FREEDMAN.
